SAFETY ARROW RELEASE DEVICE FOR BOWS IN ARCHERY

Godfrey Flury, Austin, Tex.

Application October 3, 1933, Serial No. 691,906

6 Claims. (Cl. 273—107.5)

This invention relates to new and useful improvements in a safety arrow release for the bows in archery. The invention has for an object the provision of a device adapted to manually grip the arrow and the string of the bow simultaneously during the archery practice so as to eliminate the necessity of gripping the arrow and the string of the bow with tips of fingers. It is undesirable to grip the string particularly with fingers in that after even a little use of the bow and arrow, the fingers and hand will become sore from the strain. This is particularly true if the person's skin is soft, for example upon the hand of a woman. With the instant arrangement, women will more readily take to playing the game.

Still further the invention proposes an arrangement of a pair of pivoted jaws adapted to grip and hold the arrow and the string of the archer's bow and arrow, and a peculiar arrangement of handles extending from said jaw so as to extend into the hand of the archer in a most advantageous manner.

More particularly it is best to construct one of the handles of a shape so as to rest within the palm and to construct the other of the handles of a shape so that the fingers may engage upon the outer side thereof to permit convenient squeezing with the hand.

Still further the invention proposes a resilient means associated with the jaw so as to naturally cause the jaw to be pivoted open.

As another object of this invention it is particularly proposed to arrange a hood upon the handle intended for engagement with the fingers, so as to protect the fingers.

Still further the invention proposes arranging the handles which extend into the palm so as to continue down to the wrist, and to provide a strap attached upon the wrist portion of the handle engageable around the wrist so that the device may be strapped upon one's hand.

Still further the invention contemplates an adjustment whereby the handles may be adjusted to better suit the hand of a particular person.

Still further the invention proposes the construction of a device as mentioned which is simple and durable and which may be manufactured and sold at a reasonable cost.

For further comprehension of the invention, and of the objects and advantages thereof, reference will be had to the following description and accompanying drawings, and to the appended claims in which the various novel features of the invention are more particularly set forth.

In the accompanying drawings forming a material part of this disclosure:

Fig. 1 is an illustration of a young man operating an archer's bow and arrow with a safety arrow release according to this invention. 5

Fig. 2 is an inside enlarged view of the hand of the person illustrated in Fig. 1 which is holding the release device.

Fig. 3 is a side elevational view of Fig. 2, and a portion thereof broken away so as to illustrate 10 interior parts the device being shown with the jaws closed as though in the active position.

Fig. 4 is a view similar to Fig. 2 but illustrating the device without the hood.

Fig. 5 is a sectional view taken on the line 5—5 15 of Fig. 4.

Fig. 6 is a side elevational view of Fig. 4 seen as though looking from the top of the figure, the device being shown with the jaws closed as though in the active position. 20

Fig. 7 is a view similar to Fig. 2 but illustrating a slight modification.

Fig. 8 is a view similar to Fig. 4 but showing the device turned with the bottom side up.

Fig. 9 is a sectional view taken on the line 25 6—9 of Fig. 6.

Fig. 10 is a side elevational view of Fig. 8, looking in the direction of the line 10—10, of Fig. 8 the device being shown with the jaws closed as though in the active position. 30

Fig. 11 is a reduced view similar to Fig. 6 but showing a modified form of the invention the device being shown with the jaws closed as though in the active position.

Fig. 12 is a bottom view of Fig. 10. 35

In Fig. 1 the archer's bow and arrow is shown to comprise a bow 10' with a conventional string 11' and an arrow 12'. A person is shown holding the bow and arrow as though aiming it prior to shooting. It should be noticed that the hand at the rear of the arrow 12' is not gripping the arrow or the string but a device which holds these parts. This device constitutes the invention. 40

The safety arrow release comprises a pair of jaws 10 and 11 pivotally mounted upon a pin 12 and adapted to grip and hold the rear of the arrow 12' and the string 11'. More particularly the opposed faces of the jaw are provided with inserts 13, see Fig. 5, forming an opening into which the end of the arrow 12' may engage. The inside face 45 of the jaws 10 and 11 are also formed with a vertical opening 14 through which the string 11' may pass. This may best be understood by viewing Fig. 6 in which the string is clearly illustrated. 50 The front ends of the jaws 10 and 11 are formed 55

with enlarged portions 15 merely to provide a joint contact with the string 11'. This may be understood by examining Fig. 4.

The jaws 10 and 11 have rearwardly extending handles relative to the pivot 12 and these handles being arranged on opposite sides of the jaws, each jaw relative to the handle, that is, the handle 16 connects with the jaw 10 and the handle 17 with the jaw 11. One of the said handles is shaped to fit within the palm of the archer. More particularly, this is, the handle 16 and it is shown constructed at the ends with an egg-shaped portion, see Figs. 2 and 4 to snugly fit within the palm. The other handle, the handle 17 is arranged substantially at right angles to the handle 16 and is shaped so that the fingers may engage over the top edge and cause the outer face thereof, to conveniently press the handle together. The handle 17 is shaped similar to a sea shell and is connected at one edge upon the rear of the jaw 11. With this arrangement it is possible that the rear end of the jaw 11 may be disposed between the index finger and the adjacent finger between the second and third fingers so that the fingers themselves may be conveniently engaged over the outside of the handle 17. This will be readily understood from an inspection of Figs. 2 and 3.

A resilient means is provided for normally holding the jaws open. This means comprises a spring 18 disposed in between the rear ends of the jaws 10 and 11. This spring has its ends engaged into recesses formed upon the opposite inner faces of the inner ends of the jaws. A hood 19 engages over the handle 17 and is attached at its edges upon the edges of the handle. This hood is so arranged that the fingers may engage therein and thus the finger tips are protected.

The operation of the device may be understood by inspecting Fig. 1 and realizing that the hand is closed upon the handles 16 and 17 so as to hold the jaws 10 and 11 closed and so hold the end of the arrow 12^a and the string 11'. After correct aim is taken it is merely necessary to open the hand so that the spring 18 bends the jaws 10 and 11 and the string and arrow is shot. The arrow 12^a is shown with feathers 12' in Figs. 4 and 6 at the rear end so as to cause the arrow to travel straight. A feature of the invention is the convenient arranging of the handles 16 and 17 so that one handle nestles in the palm while the other handle may be engaged by the fingers. This particular construction is exceptionally convenient for the purpose it is desired.

In Fig. 7 a slight variation of the invention has been disclosed which comprises a strap 20 attached upon one end of the handle 16 and adapted to engage around the back of the hand and be attached through an opening 21 upon the other end of the handle 16. In Fig. 7 only a portion of this strap has been illustrated which is thought sufficient for an understanding of the construction.

In Figs. 8 and 10 a modified form of the device has been disclosed in which the handle 16' is of a slightly different shape from that in the prior form. In this form the handle 16' has a curved portion 22 for extending into the palm and then a continuation 23 to extend all the way down to the under side of the wrist. A strap 24 is attached upon the continuation 23 and is adapted to be wound around the wrist for holding the device upon one's hand. The strap 24 is shown broken, but must be of sufficient length so that it may be wound several times and then tied or have its end slip under one of the turns.

In Figs. 11 and 12 another modification of the invention has been disclosed in which an arrangement is provided for changing the angular position of the handles. More particularly, the handles 16 and 17 are separate from the rear ends of the jaws 10 and 11 and connected thereto by overlapping portions secured together with bolts and wing nuts 25. The adjacent portions of the overlapping portions of the handles in the rear ends of the jaws are formed with serrations or roughened portions 26 so that the handles will maintain adjusted positions. This arrangement is of advantage in that the position of the handles may be changed for the convenience of the operator for example, examining Fig. 3, it will be recognized that the fingers of the hand are not completely closed down upon the palm. Some operators may wish the angle between the handles smaller and others greater, and with the arrangement of the adjustments this is possible.

While I have shown and described the preferred embodiment of my invention, it is to be understood that I do not limit myself to the precise construction herein disclosed and the right is reserved to all changes and modifications coming within the scope of the invention as defined in the appended claims.

Having thus described my invention, which I claim as new, and desire to secure by United States Letters Patent is:

1. A safety arrow release for bows and arrows in archery, comprising a pair of pivoted jaws adapted to grip and hold the arrow and the string of an archer's bow and arrow, and rearwardly extending handles on said jaws, one of said handles being shaped to fit in the palm of the hand of the archer, and the other of said handles being shaped so that the fingers may engage over the edge and against the outer face so that the handles may be conveniently pressed together, said handles being substantially at right angles to each other when in gripping position.

2. A safety arrow release for bows and arrows in archery, comprising a pair of pivoted jaws adapted to grip and hold the arrow and the string of an archer's bow and arrow, and rearwardly extending handles on said jaws, one of said handles being shaped to fit in the palm of the hand of the archer, and the other of said handles being shaped so that the fingers may engage over the edge and against the outer face so that the handles may be conveniently pressed together, said handle for engagement by the fingers being substantially of shell shape and connected at one edge upon the rear end of the jaw.

3. A safety arrow release for bows and arrows in archery, comprising a pair of pivoted jaws adapted to grip and hold the arrow and the string of an archer's bow and arrow, and rearwardly extending handles on said jaws, one of said handles being shaped to fit in the palm of the hand of the archer, and the other of said handles being shaped so that the fingers may engage over the edge and against the outer face so that the handles may be conveniently pressed together, and a hood attached at its edges upon the edges of said handle for engagement by the fingers so that the tips of the fingers may engage in the hood.

4. A safety arrow release for bows and arrows in archery, comprising a pair of pivoted jaws adapted to grip and hold the arrow and the string of an archer's bow and arrow, and rearwardly extending handles on said jaws, one of said handles being shaped to fit in the palm of the hand of the archer, and the other of said handles being

shaped so that the fingers may engage over the edge and against the outer face so that the handles may be conveniently pressed together, and a strap attached upon one of said handles for securing the device upon one's hand.

5. A safety arrow release for bows and arrows in archery, comprising a pair of pivoted jaws adapted to grip and hold the arrow and the string of an archer's bow and arrow, and rearwardly extending handles on said jaws, one of said handles being shaped to fit in the palm of the hand of the archer, and the other of said handles being shaped so that the fingers may engage over the edge and against the outer face so that the handles may be conveniently pressed together, and a strap attached upon one of said handles for securing the device upon one's hand, said strap being attached upon the handle attached to fit in the palm.

6. A safety arrow release for bows and arrows in archery, comprising a pair of pivoted jaws adapted to grip and hold the arrow and the string of an archer's bow and arrow, and rearwardly extending handles on said jaws, one of said handles being shaped to fit in the palm of the hand of the archer, and the other of said handles being shaped so that the fingers may engage over the edge and against the outer face so that the handles may be conveniently pressed together, and a strap attached upon one of said handles for securing the device upon one's hand, said strap being attached upon an extension from the handle adapted to fit in the palm, said extension being in the vicinity of the wrist so that the strap may 10 be engaged around the wrist.
